[57] CLAIM

The ornamental design for combined housing and
mounting bracket for vehicle lamp or mirror, as shown
and described.

DESCRIPTION

FIG. 1 is a top, front, right side perspective view of a
combined housing and bracket for vehicle lamp or mirror
showing my new design;

FIG. 2 is a bottom, rear, left side perspective view
thereof on an enlarged scale;

FIG. 3 is a rear elevational view thereof;

FIG. 4 is a left side elevational view thereof;

FIG. 5 is a right side elevational view thereof;

FIG. 6 is a front elevational view thereof;

FIG. 7 is a top plan view thereof.
